UNITED STATES PATENT OFFICE.

ELIAS WIRTH-FREY, OF AARAU, SWITZERLAND.

METHOD OF INSPISSATING LIQUIDS.

1,405,244.

Specification of Letters Patent. Patented Jan. 31, 1922.

Application filed March 15, 1919. Serial No. 282,980.

To all whom it may concern:

Be it known that I, ELIAS WIRTH-FREY, a citizen of the Swiss Confederation, and residing at Aarau, Switzerland, have invented 5 certain new and useful Improvements in Methods of Inspissating Liquids, of which the following is a specification.

The present invention has reference to a new and improved method or process for 10 thickening liquid by evaporation, and relates more specifically to an inspissating operation in which the steam or vapor rising from the liquid under treatment is drawn off, is compressed, and is then used 15 over again as heating medium.

According to my invention the steam issuing from the compressor is first caused to act on the highest concentrated portion 20 of the liquid and subsequently on the rest of it of lower concentration. The operation may be carried through in such manner that the working steam fresh from the compressor is introduced first into the rearmost of a plurality of serially intercommunicating vessels, and is then conducted 25 in parallel or multiple arrangement into the other vessels. If, by way of example, in an inspissating installation four boilers I, II, III and IV are arranged in series, the 30 heating steam coming fresh from the compressor may be introduced first into the rearmost boiler IV, and from there in two parallel conduits simultaneously into the boilers II and I; or it may be led, after 35 having acted on the liquid in boiler IV, in three, relative to the steam course parallelly disposed conduits simultaneously into the boilers III, II and I.

It is well known that with increasing concentration of a liquid solution, for instance lye, its boiling point is raised and that to allow for this the working steam must correspondingly be placed under a steadily increasing pressure and thus must be compressed to an increasingly higher temperature. If for compressing a centrifugal compressor is used, either an increase in the 45 number of the working steps or an increase in the rotary speed is called for. The first 50 expedient would require an expensive construction, and the second can only with difficulty be resorted to where the rotary compressor is driven by a three phase motor.

It is in such cases that the present invention offers great advantages, as also in

inspissating plants which operate continuously and in which in one part of the boilers the solution still shows a weak concentration whilst in the other part already a more advanced state of concentration obtains, and 60 it is here that my invention effectively deals with the touched-on phenomenon that the more strongly concentrated solution possesses a higher boiling point and therefore requires a heating medium of higher temperature for transferring a certain number of calories in a given period of time, than does a portion of the solution still in the initial weakly concentrated state.

My invention will best be understood when 70 described in connection with the accompanying sheet of drawings, in which is shown in diagrammatic section an apparatus operating on three serially connected boilers.

In the arrangement shown in the draw- 75 ing the boilers 21, 22 and 23 are connected in series. The lye enters the vessel 21 through pipe 24, passes through pipe 25 to the next vessel 22, and then through pipe 26 into the last vessel 23, from where it 80 finally flows off in concentrated state through pipe 27. The lye steam forming in the three boilers is drawn out of them by the centrifugal compressor 29 through the common conduit 28, is compressed and is then sent 85 through pipe 30 to the rearmost boiler 23, wherein the heating steam gives off part of its heat. The steam in the pipe 30 will be in superheated state due to the preceding compression, but its degree of superheat, 90 obviously, decreases during its passage through the boiler 23, so that the steam issuing from this boiler will be found to be only slightly superheated or even already saturated. From the vessel 23 the one half 95 of the heating medium passes through pipe 31 into the heating chamber of the boiler 22, whilst the other half passes through pipe 32 into the boiler 21, where it condenses completely. The condensate runs off from the boilers 22 and 21 through the pipes 33 and 34 respectively.

Back of the heating chamber of the boiler 23 the steam may be passed through a water separator 35 prior to being inducted into 105 the boilers 22 and 21.

To compensate for loss of heat during the operation, fresh steam may be introduced into the boiler 1, but where the boilers and the pipes for conducting the heating medium 110

and the liquid to be treated are well insulated, the loss of heat will be practically nil.

What I claim is:

5. The method of inspissating liquids in a plurality of serially intercommunicating concentrating vessels, which consists in causing the steam supplied by a compressor to

act first entirely on the contents of the last one in the series of vessels and then 10 simultaneously in parallel arrangement on the contents of the other vessels.

ELIAS WIRTH-FREY.
